VARIABLE CONDENSER.

Application filed July 26, 1924. Serial No. 728,480.

This invention relates to a condenser such as is specially adapted for the control of high frequency circuits, as for instance in radio communication systems.

5 Variable condensers having interleaving plates have been in use for a considerable period for this purpose, but as constructed they present certain disadvantageous effects that our invention is aimed to overcome.

10 These condensers are used in a large majority of instances to tune high frequency circuits so as to make them resonant to a very narrow range of frequencies, as is well understood. When so used, it is highly im-

15 portant to perform adjustments having comparatively fine effects on the circuit. With the usual type of condenser having rotary plates interleaving stationary plates, the variation in capacity cannot readily be made

20 such as to provide uniform wave length variation at which the circuit is resonant, for uniform variations in the setting; furthermore it is difficult to secure fine adjustment, the rotary plates having only about

25 a 180° movement relative to the stationary plates.

It is one of the objects of our invention to overcome these disadvantages in a large measure, and to make it possible to secure accurate adjustment as well as uniform wave length variation.

Another serious defect in condensers of the prior art resides in the fact that the insulation between the electrodes of the condenser is so distributed as to fall within relatively intense electric fields, whereby a large dielectric loss results. This in turn not only reduces the sharpness of tuning, but also the intensity of the signal. It is another object of our invention to provide a low loss condenser by removing all insulation out of the intense field.

It is also another object of our invention to provide a variable condenser having a low minimum capacity, whereby the wave length range is increased.

It is still another object of our invention to improve in general the mechanical construction of the condenser.

50 We attain these various objects mainly

by providing two sets of movable plates which interleave, the movement of the plates being more nearly simply a gradual linear movement of one set over the other. By arranging these plates so that they first 55 overlap at the corners only, the desired uniformity of wave length is obtained.

Our invention possesses other advantageous features, some of which with the foregoing, will be set forth at length in the 60 following description, where we shall outline in full that form of the invention which we have selected for illustration in the drawings accompanying and forming part of the present specification. Although we 65 have shown in the drawings but one form of our invention, we do not desire to be limited thereto, since the invention as described in the claims may be embodied in many other forms also.

70 Referring to the drawings:

Figure 1 is a top plan view of a condenser embodying our invention, shown as installed on a panel and in minimum capacity position;

Fig. 2 is a rear view of the same, showing the plates in minimum capacity position, and in alternate, maximum capacity position;

Fig. 3 is a sectional view, taken along 80 plane 3—3 of Fig. 2; and

Fig. 4 is another sectional view, taken through the supporting rod for one of the sets of plates.

The two sets of plates may be conveniently 85 designated as the left hand set 11 and the right hand set 12. In the present instance, there are fifteen plates in the left hand set, and sixteen in the right hand set, although the number may of course be varied to suit 90 the requirements as regards capacity. These sets of plates are arranged to be manually rotated by a common mechanism, about axes provided by the rods 13 and 14, which are stationary and upon which are rotatably 95 mounted the sleeves 15 and 16 respectively. Upon these sleeves are fastened, as by soldering, the plates 11 and 12, which for this purpose are provided with apertured ears 17 passing over the sleeve 15 or 16. These ears 100

in the present instance are formed at one side of the plates 11 and 12, so that as the sleeves 15 and 16 are rotated, the relative position of the plates may be varied from that shown in full lines in Fig. 3, to that shown in dotted lines, where the sets of plates substantially completely overlap each other. It is to be noted that the overlapping of the plate starts at the upper adjacent corners 18, and that the overlapping gradually spreads from that corner as the sleeves 15 and 16 are rotated. Due to this arrangement, the change in capacity with relation to the amount of rotation of the plates, is at first slow, when starting from the minimum full line position, but increases substantially uniformly as that position is departed from. Such a variation, it may be readily shown, is essential in order to secure substantial uniformity in the corresponding wave length variation of the resonant circuit controlled by the condenser.

Although all of the plates of each set are electrically connected through its respective sleeves 15 and 16, we prefer to supplement the connection by the aid of the small turned-over flaps 19 which connect adjacent plates, and which are stamped integrally with them. This further connection also serves to stiffen the plates. Furthermore, these plates are shown as substantially rectangular, but with an arched top; although to secure any desired capacity variation, this form may obviously be varied.

35 The mechanical construction whereby the movement of the plates is secured, will now be described. The rods 13, 14, upon which the sleeves 16 are rotatably mounted, are supported in any appropriate manner, as for instance, on a flat insulating plate 20. In Fig. 4 this support is shown for rod 13, but the support for rod 14 is entirely similar. Rod 13 has a collar 21 either integral or held thereto in any appropriate way, which collar engages one side of plate 20. At the other side, a washer 22 is provided, and a nut 23 engaging a threaded end of rod 13 serves to clamp the collar 21 firmly against the plate 20. In order to rotate sleeve 16 on rod 13, there is fastened to the sleeve a collar 24, to which in turn a gear wheel 25, made of bakelite or other insulating material, is held, as by the aid of the pins 26. It is thus seen that by rotating gear wheel 25, the plates 11 may be rotated about the axis of rod 13. In order to prevent the sleeve 16 from slipping off the rod 13, and also to maintain the plates 11 in proper frictional adjustment, a nut 27 is used at the free end 60 of rod 13 for engaging the end of the sleeve.

The mechanical details for operating the other set of plates are entirely similar to that already described; the operating gear 28 for the plates 12 being in mesh with gear 25, 65 whereby the rotation of one gear causes the

rotation of the other also. In this way, both sets of plates are caused to rotate in opposite directions, so as to bring them either into interleaving position or into the position shown in Fig. 2.

70 In order to lend rigidity to the structure, we preferably connect the ends of the two rods 13, 14, by a strip 29 of insulating material. On top of this strip may be placed the two terminals 30 and 31 for the condenser, 75 and the strip and terminals may be held securely to the rods 13, 14, by the aid of nuts 32. The connections to the plates 11 and 12 may thus be provided by these terminals, through rods 13 and 14, and sleeves 15, 16. 80 However, we prefer to provide a direct metallic connection from the terminals to the plates, without intervening frictional contacts. For this purpose we use the pigtail connections 33 which are soldered at one end to a terminal, and at its other end to the collar 26. The elimination of the frictional contact ensures against extraneous or parasitic noises when the condenser is used in a 85 radio system.

90 As thus far described, it is evident that the electric field existing between the sets of plates has but little influence upon any dielectric material, because all such material is at a comparatively large distance from this field. The main insulation supports are the plate 20 and the strip 29, which embrace the plates, but do not closely approach them. Due to this feature, the dielectric losses are maintained at a very low value. Furthermore the leakage paths between the electrodes are relatively long, and of small cross-sectional area, which minimizes loss due to surface leakage. Another important effect that may now be noted is that in the 95 minimum capacity position shown in Fig. 2, only the corners of the sets of plates 11 and 12 are opposite each other; there is therefore a very low minimum capacity. In other types of condensers, the sets of plates in 100 minimum position, present a comparatively large area to each other.

105 The supporting plate 20 is in turn supported back of the panel 34, as by the aid of a plurality of spacers 35 through which 110 screws 36 pass. In order to limit the movement of the plates 11 and 12 about their axes, we provide a pair of stop pins 37 on the insulation gear 25, which coact with a stationary stop pin 38 fastened in the 115 plate 20.

120 To rotate gears 25 and 28, a pinion 39 is provided, which meshes with one of them, as for instance, gear 25. This pinion is fastened to a shaft 40 that is journaled in a 125 bushing 41 held in the plate 20 and extending through the panel 34. The shaft extends for a considerable distance beyond the front of the panel, in order to make it possible to fasten thereto an operating knob 42 130

and its associated dial 43. The gear proportions are such that the dial 43 must be turned through preferably 360° to move the plates from maximum to minimum capacity position. Such an arrangement provides for accuracy in making fine adjustments, which is so important in tuning radio frequency circuits. Furthermore, it is also to be noted that no electrical connections are made through the front of the panel. This fact reduces the effect of body capacity during tuning.

In the present instance, the panel 34 is shown as fastened to a base plate 44, but it is of course evident that other modes of supporting the entire structure may be used, if desired. Furthermore, in some instances, a counterweight may be added to the sleeves 15 and 16 to balance the rotating parts of the structure, and to ensure against undesired movement of the plates by the action of gravity.

The mode of operation of the condenser is believed to be evident from the foregoing. The knob 42 is simply turned in one or the other direction until the desired setting is obtained.

Another advantage of the structure disclosed resides in the fact that any number of condensers could be geared together so as to be operated from a single knob, by merely mounting them at the proper spacing. Thus the gear 28 may be made to mesh directly with one of the operating gears of a succeeding condenser.

We claim:

1. In a variable condenser, a pair of insulated electrodes having corners, and unitary means for simultaneously moving both electrodes in such manner that they are caused to overlap to a variable extent to vary the capacity thereof, the overlapping beginning at a corner of each electrode.

2. In a variable condenser, a pair of insulated electrodes having corners arranged to provide an electrical capacity by superposition, a pair of rotatable supports, one for each electrode, said supports being so spaced that by rotation thereof the electrodes may be made to overlap to a variable extent, the overlapping beginning at a corner of each electrode, and unitary means for rotating both electrodes.

3. In a variable condenser for selectively tuning an electrical circuit, a pair of spaced shafts insulated from each other, a pair of electrodes insulated from each other and adapted to provide an electrical capacity by superposition, one electrode rotatably supported on each shaft, and gears mechanically connecting the electrodes.

4. In a variable condenser for selectively tuning an electrical circuit, a pair of insulated rotatable electrodes arranged to provide an electrical capacity by superposi-

tion, the axes of the electrodes being spaced apart, and a mechanical connection between the electrodes, whereby both electrodes may be simultaneously rotated.

5. In a variable condenser for selectively tuning an electrical circuit, a pair of insulated spaced parallel rods, an insulating support for the rods, a pair of electrodes arranged to provide an electrical capacity by superposition, one electrode rotatably mounted on each rod, and a gear fastened to each electrode and intermeshing, at least one of said gears being provided with insulation, and each of said gears being axially spaced from the corresponding electrode.

6. In a variable condenser, a pair of insulated spaced parallel rods, a pair of electrodes arranged to provide an electrical capacity by superposition, one electrode rotatably mounted on each rod, means for simultaneously rotating the electrodes so as to vary the extent of overlap between them, means for holding the rods at one of their ends, terminals fastened to the rods at the other ends, and flexible connections between the terminals and the respective electrodes.

7. In a variable condenser, a pair of electrodes, each comprising a plurality of thin parallel plates, a rotatable sleeve for each electrode to which the plates thereof are connected, a pair of spaced rods for the sleeves, gears of insulation material carried by the sleeves and intermeshing, an insulating plate on which each of the rods are fastened near one of its ends, an insulating strip connecting the free ends of the rods, a terminal for each electrode in contact with that end of the rod which is in connection with the strip, a flexible connection from each terminal to the corresponding rotatable sleeve, and a pinion engaging one of the gears.

8. In a variable condenser, a pair of insulated electrodes arranged to provide an electrical capacity by overlapping, unitary means for simultaneously moving both of the electrodes toward and from each other to vary the capacity thereof, means movably supporting said electrodes, a terminal for each electrode on said latter supporting means, and a flexible connection between the terminals and their respective electrodes.

9. A variable condenser for selectively tuning an electrical circuit comprising a base member, a pair of electrodes insulated from each other and rotatably mounted upon said base, the respective axis of rotation of the electrodes being spaced laterally, and means including a single manually controlled shaft for simultaneously rotating said electrodes in opposite directions whereby said electrodes are superposed a more or less amount to vary the capacitance of the condenser.

10. A variable condenser comprising a

base member, a pair of movable electrodes pivotally mounted upon said base member, said electrodes comprising spaced plates adapted to interleave, the pivotal axis of the electrodes being spaced laterally, control means for simultaneously moving said electrodes, movement of each electrode through

an arc of less than 180° serving to vary the capacitance from a maximum to a minimum. In testimony whereof, we have hereunto set our hands.
